UNITED STATES PATENT OFFICE

2.151.637

HYDRAULIC SURFACE GRINDING MACHINE

Carl G. Flygare and Herbert A. Silven, Worcester, Mass., assignors to Norton Company, Worcester, Mass., a corporation of Massachusetts

Application August 18, 1938, Serial No. 225,582

5 Claims. (Cl. 51—92)

The invention relates to grinding machines, and more particularly to a grinding wheel positioning and feeding mechanism for a hydraulically driven surface grinding machine.

5 One object of the invention is to provide a surface grinding machine with an automatic mechanism for positioning the wheel both in a horizontal and vertical direction. Another object of the invention is to provide a surface grinding
10 machine with a hydraulically operated mechanism for moving the grinding wheel slide transversely and vertically to position the wheel for grinding spaced plane surfaces on a work piece. Other objects will be in part obvious and in part
15 pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

25 Fig. 1 is a front elevation of the improved surface grinding machine having parts broken away and shown in section to more clearly show the operating mechanism;

Fig. 2 is a fragmentary diagrammatic view showing the hydraulic mechanism for moving the wheel slide transversely and also the hydraulically operated mechanism for moving the wheel slide vertically; and

Fig. 3 is a fragmentary sectional view taken approximately on the line 3-3 of Fig. 1, showing the control valve for controlling the admission to and exhaust of fluid from the hydraulic cylinder for positioning the grinding wheel.

Fig. 4 is a detail of the mechanism for manually moving the wheel slide transversely.

A surface grinding machine has been illustrated in the drawings having a base 10 which supports a longitudinally reciprocable work table 11. The table 11 is supported on the usual V-way and flat way (not shown) on the base 10. A grinding wheel 15 is rotatably mounted on a transversely movable wheel slide 16 which is supported by a dovetailed slideway on a vertically movable slide 17 carried by an upwardly extending portion 18 of the base 10. The vertical slide 17 is arranged for manual adjustment to position the periphery of the grinding wheel 15 relative to the surface of a work piece which is mounted on the table 11 so as to grind the surface to the

required extent. This mechanism may comprise a manually operable feed wheel 20 of the well known type such as that shown in the prior United States patent to Norton No. 1,108,779 dated August 25, 1914 and the patent to Fly-gare and Wood No. 2,022,542 dated November 26, 1935. Reference may be had to these patents for details of disclosure not found herein.

The manually operable feed wheel 20 is connected to rotate a gear 21 meshing with a gear 10 22. The gear 22 is formed with an internal threaded aperture which meshes with or engages a feed screw 23. The gear 22 is rotatably supported by anti-friction bearings 24 and 25 which are in turn supported within a casing 26 and 15 serve to hold the gear 22 against endwise movement. When the gear 22 is rotated by manual rotation of the feed wheel 20, rotation of the threaded aperture within the gear 22 causes an endwise vertical movement of the feed screw 23 20 which serves in a manner to be hereinafter described to raise and lower the vertically movable slide 11 so as to position the grinding wheel 15 vertically relative to the table 11.

A vertically arranged shaft 28 is slidably mounted within an aperture within the feed screw 23 and is slidably keyed within said aperture by means of a key 29. The lower end of the rod or shaft 28 is connected by a stud 30 with the vertically movable slide 17. 25 30 80

Table reciprocating mechanism

The table 11 is arranged so that it may be reciprocated by a power operated mechanism to pass the work piece beneath the operative face 38 of the grinding wheel 15. In the preferred form, the reciprocating mechanism comprises a fluid pressure system comprising a cylinder 35 which is fixedly mounted in the base 10. A piston 36 is slidably mounted within the cylinder 35 and is connected by a piston rod 37 to a depending bracket 38 on the under side of the table 11. The base 10 is provided with a fluid reservoir 40, from which fluid is pumped by a motor driven fluid pressure pump 41, through a pipe 42, which is arranged to force fluid under pressure through a pipe 43 to a reversing valve (not shown) within the base of the machine. Fluid under pressure is forced either through a pipe 45 to a cylinder chamber 46 at the left-hand end of the cylinder 35, or through a passage 47 into a cylinder chamber 48 at the right-hand end of the cylinder 35, so as to reciprocate the table 11 in either direction as desired. For other details of the hydraulic mechanism for reciprocating the table, 50

reference may be had to the prior United States Patent No. 2,022,542.

Reverse valve actuating mechanism

5 The reversing valve may be actuated manually or by power. As illustrated in the drawings, a manually operable reversing lever 50 is pivotally mounted on a stud which is fixed to the base 10. A depending portion 51 of the lever 50 is provided with a gear segment 52 which meshes with a gear segment 53 mounted on the outer end of a rock shaft, the inner end of which is connected through a gear to rotate the reversing valve. It will be readily apparent from the foregoing disclosure that when the lever 50 is rocked in either direction, motion will be transmitted through the gear segments 51 and 52 to actuate the reversing valve. In order that the reversing valve may be shifted rapidly into a reverse position after the 10 lever has moved toward a central position, a pivotal load and fire mechanism is provided. For details of disclosure of this mechanism, reference may be had to the prior United States Patent No. 2,022,542.

15 25 The lever 50 may be actuated manually or in the preferred form may be actuated in timed relation with the movement of the table 11 by adjustable dogs 60 and 61 which are adjustably mounted in a T-slot 62 formed on the front of the table 11. Assuming the table to be traveling in the direction of the arrow, as indicated, the table continues moving in this direction until the dog 60 strikes a projection on the reversing lever 50 and swings the reversing lever in a clockwise direction to shift the reversing valve into a reverse position to change the direction of flow of fluid under pressure to the cylinder 35.

Throttle valve

40 In order that the normal speed of the table may be varied to give the desired relative speed between the operative face of the grinding wheel and the work piece, a throttle device is provided which comprises a throttle valve 65 located in the exhaust side of the fluid pressure system so that the speed of the table 11 is regulated by the exhaust of fluid from the cylinder 35. The throttle valve 65 is preferably provided in an integral part of the reverse valve mechanism and is actuated by a manually operable lever 66. By manipulation of the lever 66, the operator may vary the aperture of the throttle valve 65 and thereby control the normal speed of the table.

Transverse wheel feeding mechanism

55 In grinding of plane surfaces on a surface grinding machine of the type in which the work supporting table reciprocates beneath the wheel 15, it is desirable to provide a feeding traversing mechanism to traverse the grinding wheel transversely at the end of a table stroke so as to present the wheel face to a different portion of the work on the next table stroke. It is desirable to provide such a mechanism with a power actuated device which operates automatically to index or 60 traverse the grinding wheel transversely at either or both ends of the table stroke. As illustrated in the drawings, a fluid pressure cylinder 70 is mounted within the vertically movable slide 17. A slidable piston 71 within the cylinder 70 is connected by a piston rod 72 to a bracket 73 which projects rearwardly from the wheel slide 16. A reversing valve 74 is provided to permit changing the direction of movement of the slide 16. The valve 74 is preferably of the balanced piston 75 type, in which fluid under pressure from a pump

75 is conveyed through a pipe 76 and a pipe 77 to a valve chamber 78. In the position illustrated in Fig. 2, fluid under pressure entering the valve chamber 78 passes through a passage 79 into a cylinder chamber 80 at the right-hand end of the cylinder 70. During this movement, fluid is exhausted from a cylinder chamber 81 at the other end of the cylinder 70, through a passage 82, into a valve chamber 83, and out through a pipe 84 and a pipe 85 which returns it to the reservoir 40 in the base 10. The pump 75 has been shown diagrammatically in Fig. 2 as a separate pump unit. This pump may be a separately operated independently motor driven pump or may be combined with fluid pressure pump 41 as a tandem 15 pump unit driven by a single electric motor.

The valve 74 is provided with a valve stem 86 and an actuating knob 87. When the knob 87 is moved toward the left (Fig. 2) to shift the reversing valve 74 into the reverse position, fluid 20 under pressure passing through the pipe 77 into the valve chamber 78 passes through the passage 82 into the cylinder chamber 81 to cause the wheel slide 16 to move toward the right (Fig. 2). During this movement, fluid exhausts from the 25 cylinder chamber 80, through the passage 79, through a valve chamber 88, and out through the pipes 84 and 85 to the reservoir. By manually shifting the valve 74 by means of the manually operable knob 87, the wheel slide may be moved 30 by fluid under pressure in either direction to position the grinding wheel 15 for grinding the plane surface of a work piece.

If desired, the wheel slide 16 may be provided with a dog bar 90 and adjustable dogs 91 (Fig. 3), 35 only one of which has been illustrated, which are arranged in the path of a projection 92 of a reversing lever which is arranged to shift the valve 74 automatically in timed relation with the transverse movement of the slide 16 so as to automatically reverse its direction of movement 40 after it has traversed a predetermined extent in either direction. This mechanism has not been illustrated in detail in the present case since it is not considered a part of the present invention. 45 For further details of construction of this automatic reversing mechanism for the valve 74, reference may be had to the above-mentioned prior United States Patent No. 2,022,542.

To attain one of the main objects of the invention, it is desirable to provide a rapid vertical positioning movement for the wheel 15. In grinding work pieces on a surface grinding machine of this type having spaced plane surfaces which are arranged at different horizontal levels, it is necessary to position the wheel 15 at different levels for grinding the spaced surfaces thereon. In the preferred form, it is desirable to provide an automatically actuated mechanism, such as a hydraulically operated mechanism comprising 60 a cylinder 100 which is supported on the upper end of the feed screw 23. A piston 101 is slidably mounted within the cylinder 100 and is fixedly connected to the upper end of the rod 28 which serves as a piston rod. When fluid under pressure is admitted through a pipe 102 into a cylinder chamber 103 at the lower end of the cylinder 100, the piston 101 is moved upwardly, causing an upward movement of the piston rod 28 relative to the feed screw 23 and, through the connecting 70 stud 30, causing a vertical movement of the vertically movable slide 17 to rapidly raise the wheel slide 16 and the grinding wheel 15 to a different position. The upward vertical movement of the piston 101 may be limited by means 75

of an adjustable stop screw 104. During the upward movement of the piston 101, fluid within a cylinder chamber 105 above the piston 101 is exhausted through a pipe 106 in a manner to be hereinafter described.

A control valve 110 is provided for controlling the admission and exhaust of fluid to and from the cylinder 100. The control valve 110 is preferably a piston type valve comprising a valve stem 111 having formed integrally therewith valve pistons 112, 113, 114, 115 and 116. The valve 110 is shown in its downward position (Figs. 2 and 3). A roller 118 is rotatably supported by a stud 119 on the lower end of the valve stem 111 and is arranged to ride on a cam surface 120 which is fixedly supported on a bracket 121 projecting from the wheel slide 16. A spring 122 which is supported in an aperture in the upper end of the valve piston and interposed between the bottom of the aperture and the valve head serves to maintain the roller 118 in operative engagement with the cam 120.

When the wheel slide 16 is traversed transversely either manually by a manually operable mechanism, such as that shown in the prior United States Patent No. 2,022,542, or by fluid under pressure as disclosed above, the cam 120 traverses with the slide and the roller 118 following the cam serves to change the position of the valve so as to control the admission of fluid to and from the cylinder 100. When the wheel slide 16 is moved so as to traverse the cam 120 toward the right (Fig. 3), the roller 118 will ride up the inclined surface of the cam 120 onto a horizontally extending portion 123 to shift the valve so as to reverse the direction of flow of fluid.

Fluid under pressure passing through the pipe 16 enters a valve chamber 125 between the valve pistons 113 and 114 and passes out through a port 126 into the pipe 106 to apply fluid under pressure to the cylinder chamber 105 to move the piston 101 in a downward direction. During this movement, fluid within the cylinder chamber 103 exhausts through the pipe 102, a port 127, into a valve chamber 128, and passes out through a port 129 and exhausts through the pipe 85 into the reservoir 40. When the cam 120 is traversed toward the right (Fig. 3) to cause the valve to move in an upward direction, the direction of flow of fluid to the cylinder 100 is reversed. In this position of the valve, fluid under pressure from the pipe 16 enters the valve chamber 125 and passes out through the port 127 and pipe 102 into the cylinder chamber 103 to cause the piston 101 to move in an upward direction. During the upward movement of the piston 101, fluid within the cylinder chamber 105 exhausts through pipe 106, the port 126, into a valve chamber 130, and passes out through a port 131, into the pipe 85, to return to the reservoir.

During the vertical positioning movement of the grinding wheel 15 and the transverse setting thereof to position the wheel for grinding in a second position on the work piece, it may be desirable in grinding certain types of work to cut off the fluid pressure traversing movement so that the wheel slide may be positioned manually for grinding the second portion on a work piece. During the normal operation of the machine, fluid under pressure passing through the pipe 16 also passes through a pipe 135 and a port 136 into a valve chamber 137 located between the valve pistons 115 and 116 and passes out through a port 138, into the pipe 77 which conveys fluid under pressure to the valve 110 which controls

the transverse movement of the wheel slide 16. When the roller 118 rides onto the upper level portion 123 of the cam 120 to cause the grinding wheel 15 to rise vertically to facilitate repositioning the wheel to grind a second portion on a work piece, the valve piston 115 covers the port 136 and thereby cuts off fluid from the pipe 77 to prevent fluid pressure traverse of the wheel slide 16. By varying the shape of the cam 120, the grinding wheel slide 16 may be moved vertically to an inoperative position at one or more stations during its transverse movement in accordance with the nature of the work being ground.

In grinding spaced plane surfaces on a work piece which are in different horizontal planes, it may be desirable that the power transverse feed of the grinding wheel slide 16 be continuously operated and the vertical positioning mechanism be arranged independent of the transverse feeding mechanism so that it may be readily controlled. A by-pass pipe 139 is connected between the pipes 16 and 77 and a shut-off valve 140 is provided in the pipe line 139. When the valve 140 is opened, fluid under pressure may pass continuously through the pipe 77 to the valve 14 and independently of the control valve 110 which controls the admission of fluid to the cylinder 100. In the open position of the valve 140, the wheel slide 16 may be indexed transversely and intermittently at the ends of the reciprocatory stroke of the work table 11 by a mechanism shown in detail in the prior United States Patent No. 2,022,542 to which reference may be had for details of disclosure. During the transverse movement of the wheel slide, the roller 118 after travelling across the lower horizontal plane of the cam 120 to grind one portion of the work piece, travels up the rise in the cam to the second or upper level 123 which shifts the valve stem 111 upwardly in a vertical direction to admit fluid under pressure from the pipe 16 into the chamber 125 and out through the pipe 102 into the cylinder chamber 103 to vertically move the vertical slide 17 to position the grinding wheel 15 for grinding a second portion of the work piece which is in a different horizontal plane from the first ground surface. The wheel slide 16 is continuously and intermittently indexed transversely to grind first the surface on the lower level wherein the valve is controlled by the surface 120 and the cam and then to grind the second surface wherein the valve is controlled and positioned by the surface 123 on the cam.

This mechanism may also be utilized for grinding two spaced portions of a work piece which are interposed by a central rib or projection located between the plane surfaces to be ground. By modifying the shape of the cam 120, the valve 110 may be shifted as the grinding wheel approaches the rib or obstruction on the work piece to raise the grinding wheel to an uppermost or inoperative position until the wheel passes over the rib or obstruction and then the valve 110 is shifted downwardly again to shift the grinding wheel back into an operative position for grinding the second spaced portion on the work piece. Such a cam shape has been represented by a dotted line cam face 150 (Fig. 3).

The operation of this improved surface grinding machine will be readily apparent from the foregoing disclosure. The grinding wheel slide 16 may be positioned transversely by actuation of the valve 14 by means of the knob 81 to position the wheel in its initial relation with the work to grind a portion thereof. The wheel may be

- raised or lowered vertically by manual actuation of the feed wheel and the wheel slide 16 may be manually adjusted transversely by rotation of the manually operable wheel 140. The hand wheel 5 140 is mounted on the outer end of a shaft 141. The inner end of the shaft 141 supports a bevel gear 142 (Fig. 4) which meshes with a bevel gear 143. The bevel gear 143 is mounted on one end of a shaft 144 which is rotatably journaled in 10 the vertically movable slide 17. The other end of the shaft 144 carries a pinion or gear 145 which meshes with a rack bar 146 which is fixedly mounted on the slide 16 so that when the wheel 140 is rotated in either direction, a transverse 15 movement will be transmitted to the slide 16.
- After the first portion of the work piece has been ground to the predetermined extent, the wheel slide 16 is moved transversely so that the cam 120 moves toward the right (Fig. 3) to shift 20 the valve stem 111 upwardly into the reverse position, which serves automatically to cut off fluid from the control valve 74 and prevent hydraulic traverse of the wheel slide 16 and at the same time serves to admit fluid under pressure through 25 the pipe 102 to raise the piston 101 vertically to raise the vertical slide 17 and the grinding wheel 15 to an inoperative position while positioning the wheel for grinding a second portion of the work piece or while shifting to a second 30 level for grinding a portion of the work piece to a different thickness.
- It will thus be seen that there has been provided by this invention apparatus in which the various objects hereinabove set forth together 35 with many thoroughly practical advantages are successfully achieved. As many possible embodiments may be made of the above invention and as many changes might be made in the embodiment above set forth, it is to be understood that 40 all matter hereinbefore set forth or shown in the accompanying drawings is to be interpreted as illustrative and not in a limiting sense.

We claim:

1. In a surface grinding machine, a rotatable 45 grinding wheel, a transversely movable wheel slide, a vertically movable slide to support said transverse slide, a longitudinally reciprocable work supporting table, a separate power operated actuating mechanism for each of said slides and said table, and means including a cam on said wheel slide which actuates the power mechanism for the vertical slide to position the grinding wheel vertically.
2. In a hydraulically operated surface grinding 50 machine, a rotatable grinding wheel, a transversely movable wheel slide, a vertically movable slide to support said transverse slide, a longitudinally reciprocable work supporting table, a separate

fluid motor for each of said slides and said table, a separate control valve for each of said motors, and a cam on said wheel slide which actuates the control valve for the vertical slide motor, vertically positioning the grinding wheel.

3. In a hydraulically operated surface grinding machine, a rotatable grinding wheel, a transversely movable wheel slide therefor, a vertically movable slide to support said transverse slide, a longitudinally reciprocable work supporting table, a separate fluid motor for each of said slides and said table, a separate control valve for each of said motors, the control valves for said vertical and said transverse slide motors being interlocked to prevent transverse slide motors being interlocked to prevent transverse movement of the wheel slide when the vertical valve is shifted to raise the grinding wheel.

4. In a hydraulically operated surface grinding machine, a rotatable grinding wheel, a transversely movable wheel slide, a vertically movable slide to support said transverse slide, a longitudinally reciprocable work supporting table, a separate fluid motor for each of said slides and said table, a separate control valve for controlling each of said motors, said control valve for the vertical slide motor being mounted on the vertical slide, a follower roller on said valve, and a cam on said wheel slide which engages said follower and serves to actuate the latter control valve when the wheel slide is traversed transversely automatically to position the grinding wheel for grinding spaced portions on a work piece in different horizontal planes.

5. In a hydraulically operated surface grinding 35 machine, a transversely movable wheel slide, a vertically movable slide to support said transverse slide, a longitudinally reciprocable work supporting table, a separate fluid motor for said wheel slide and said table, a control valve for each of said motors, a manually operable nut and screw feed mechanism to move said vertical slide to position the grinding wheel relative to the table, a cylinder carried by said feed screw, a piston slidably mounted therein, a piston rod slidably keyed 40 within a central aperture in said feed screw, the upper end of said piston rod being connected to the piston and the lower end being connected to said vertical slide, a control valve to control the admission of fluid to said cylinder, and means including a cam on said transverse slide to actuate said valve to admit fluid under pressure to said latter cylinder to cause a vertical movement of said vertical slide relative to the nut and screw feeding mechanism to position the grinding wheel 45 for grinding spaced surfaces on a work piece.

CARL G. FLYGARE.
